FREQUENCY-STABILIZED WAVE-SIGNAL APPARATUS

Albert E. Hayes, Jr., West Hartford, Conn., assignor to Hazeltine Research, Inc., Chicago, Ill., a corporation of Illinois

Application July 5, 1946, Serial No. 681,453

5 Claims. (Cl. 179—171.5)

1.

This invention relates to an improved frequency-stabilized wave-signal apparatus, and more particularly to such an apparatus including a generator of wave signals to which is coupled means for amplitude modulating the wave signals. While the invention is subject to a wide range of applications, it is especially suited for use in a vacuum-tube oscillator for generating modulated wave signals and will be particularly described in connection with apparatus containing such an oscillator.

It is conventional in radio apparatus to utilize as a generator of wave signals a vacuum-tube oscillator including one or more tuned oscillatory circuits, containing either lumped or distributed reactances, for controlling the frequency of the oscillator. Several systems have been devised for automatically controlling the oscillating frequency, for example, to prevent slow frequency changes, the control effect being proportional to the deviation of the frequency from the resonant frequency of an auxiliary tuned circuit. It usually is considered advisable, however, to maintain only loose coupling between the oscillator circuits and any amplifying or modulating circuits in order to avoid deviation of the oscillation frequency due to faulty tuning or slow frequency drifting of the oscillator circuits, but rather to changes occurring in the amplifying or modulating circuits. When it is necessary to couple such other circuits rather closely to the circuits of the oscillator itself, various arrangements have been developed for minimizing deviation of the frequency of the signals generated by the oscillator. One of these arrangements, for application to the local oscillator of a superheterodyne receiver, includes a multi-element vacuum tube having a section used as an oscillator and another section used as a modulator, three of the elements being used as a triode local oscillator and the remaining elements including the anode electrode being used as the modulator or first detector. One of these remaining elements is a control electrode to which is applied a voltage derived for the purpose of automatic amplification control. As this voltage changes from time to time in accordance with the average strength of the received signal, the frequency of the signal generated by the local oscillator tends to change. This effect is diminished by furnishing a suitable reactive coupling from the anode circuit of the first detector to the frequency-determining circuits of the local oscillator. In that arrangement, however, none of the circuits are intended to amplitude modulate or

to change in any way the signal present in the circuits of the triode local oscillator itself, nor is the modulating signal used to modify or control the oscillating frequency of the local oscillator. The purpose of that arrangement is in fact to prevent any kind of change in the signal of the local oscillator regardless of what occurs in other circuits coupled to that oscillator.

When it is desired to produce a wave signal of a constant carrier frequency and also to effect amplitude modulation of this wave signal, it has become almost universal practice to use an additional stage or stages of amplification following the circuits in which the oscillations are generated. The signal present in one of these amplifying stages is then modulated, and the coupling between this modulator stage and the oscillator stage is maintained sufficiently small to prevent any modulation of signals in the oscillator itself. In certain cases it has proved feasible to apply audio or other signals directly to the circuits of an oscillation generator to amplitude modulate the signal generated therein, but only very low percentages of modulation are permissible, especially with generators of the higher radio-frequency oscillations. If it is attempted to modulate the generated signal at all heavily by means coupled directly to such generator, excessive deviation of the carrier frequency tends to occur during modulation, resulting in distortion of the amplitude-modulated wave and an excessively wide band of frequency transmission.

Accordingly, it is an object of this invention to provide a new and improved frequency-stabilized wave-signal apparatus which substantially avoids one or more of the limitations of the described prior arrangements.

It is a further object of this invention to provide a new and improved frequency-stabilized wave-signal apparatus for generating amplitude-modulated wave signals which has an arrangement for diminishing deviation of the carrier frequency during modulation.

In accordance with the invention, a frequency-stabilized wave-signal apparatus comprises a generator of wave signals of predetermined carrier frequency and means effective to vary the amplitude of the wave signals generated by the generator in accordance with a modulating signal to produce an amplitude-modulated wave signal but tending to cause undesired deviation of the frequency of the wave signals generated by the generator. The apparatus also comprises means coupled to the wave-signal generator and effective to modify its carrier frequency and means

for utilizing the same modulating signal to control the last-named means substantially to diminish the undesired deviation of the carrier frequency.

For a better understanding of the present invention, together with other and further objects thereof, reference is had to the following description taken in connection with the accompanying drawing, and its scope will be pointed out in the appended claims.

In the drawing, there is shown a schematic circuit diagram illustrating in detail one embodiment of the invention.

Referring to the drawing, there is shown schematically a transmitting apparatus for producing an amplitude-modulated wave signal of stabilized carrier frequency. The major parts of the apparatus comprise a source 10 of a modulating signal such as an audio voltage, an audio amplifier 11, a generator 12 of wave signals of predetermined carrier frequency, and a utilization means 13 for the output generator 12, the foregoing units being connected in cascade, and also a frequency-modifying circuit 14 coupled to generator 12.

More specifically, the amplifier indicated generally at 11 comprises a vacuum tube 20 having a control electrode 21, which is coupled to source 10 by means of an audio transformer 22 with a grounded electrostatic shield, the coupling being effected through a polarity reversing switch 23. The anode-cathode circuit of amplifier tube 20 includes the conventional self-biasing arrangement 24 and contains the primary of output transformer 25 and a by-pass condenser 26, the circuit being supplied with space current from a source indicated B+. The amplifier 11 is coupled through the secondary of transformer 25 to the anode of an electron-discharge means comprising an oscillator tube 30 included in the generator 12, carrier-frequency energy being excluded from the amplifier 11 by carrier-frequency choke 31. Tube 30 also is supplied with space current from the source B+, and has a conventional self-biasing arrangement 32 in its control-electrode circuit. Also included in generator 12 is a frequency-determining oscillatory circuit, comprising an inductor 33 and an adjustable condenser 34 coupled to the control electrode of tube 30 through the biasing arrangement 32 and to the anode of tube 30 through a blocking condenser 35. A tap on inductor 33 is connected to ground and the cathode of tube 30, thus completing the circuit arrangement of an oscillator of the Hartley type. The utilization means 13 is an antenna circuit, including an output inductor 36 tuned by a condenser 37 and coupled to antenna 38.

The frequency-modifying means 14 includes an additional electron-discharge means in the form of a tube 40 having an anode 41, a cathode 42 and at least one control electrode 43. Connection 45 connects the anode electrode of oscillator tube 30 to the anode 41 of tube 40, thus providing a source of space current for tube 40. Cathode 42 is connected to ground through a biasing resistor 44 and an audio-frequency bypass condenser 45. Thus the anode-cathode circuit of tube 40 is coupled to the frequency-determining oscillatory circuit, including inductor 33 and adjustable capacitor 34 through the connection 45 and condenser 35, and through the condenser 45 and the grounded tap on inductor 33.

The frequency-modifying unit 14 also includes

a phase-splitting means comprising a resistor 47 in series with a condenser 48. The point common to resistor 47 and condenser 48 is connected to control electrode 43, and the other terminal of condenser 48 is connected to cathode 42, so that condenser 48 is shunted with the inherent capacitance 49 of the cathode control-electrode circuit of tube 40. The other end of resistor 47 is coupled to anode 41 through a blocking condenser 50. Screen-electrode voltage is supplied to pentode 40 through resistor 51. The control electrode 43 is coupled through a signal-frequency choke 52 to a selected portion 54 of a voltage divider 55, while the portion 54 is grounded to place it in the cathode control-electrode circuit of tube 40. Voltage divider 55 is provided with connections to the source 10 of audio signals. The signal-frequency choke 52 should have an inductance high enough so that resonance with phase-splitting condenser 48 and the inherent capacitance 49 is avoided, but not so high as to block audio-frequency signals from passing to control electrode 43.

In the operation of the circuits illustrated, a modulating signal appears at the terminals of source 10. The signal voltage varies in accordance with intelligence desired to be impressed upon the wave signals generated in unit 12 and, as illustrated, may contain audio-frequency components corresponding to speech or musical signals to be transmitted. Of course, other forms of intelligence, such as the video-image signals used in television systems, also may be used in an apparatus similar to the one illustrated in the drawing, except that circuit modifications would be necessary as is well known to ensure transmission of the wide band of frequencies required in television systems. The modulating signal is amplified in unit 11 and applied through choke 31 to unit 12, which generates carrier-frequency wave signals having amplitude variations corresponding to the audio signal amplified in unit 11. Modulation of the carrier-frequency signals in unit 12 tends to cause undesired deviation of the carrier frequency. Unit 14 is included in a means coupled to unit 12 and effective to modify the carrier frequency of the wave signals generated therein in a manner more fully described hereinafter. Voltage divider 55 by virtue of its connection through choke 52 to control electrode 43 of tube 40 provides for unit 14 a control arrangement connected to source 10 so as to utilize the modulating signal in source 10 to control the unit 14 in order substantially to diminish the deviation of the carrier frequency caused by modulation. Thus, the carrier frequency is stabilized. Antenna circuit 13 radiates the amplitude-modulated frequency-stabilized wave signal produced by the described apparatus.

Describing more specifically the operation of the circuits shown in the drawing, modulating signals from source 10 appear in the secondary of transformer 22 and are applied to control electrode 21 of tube 20 with a polarity chosen by means of reversing switch 23. Self-biasing arrangement 24 is adjusted in the usual manner to ensure that tube 20 operates on the desired portion of its control-voltage anode current characteristic. The current in the primary of output transformer 25 varies in accordance with the audio signals applied to control electrode 21, causing similarly varying voltages to appear across the secondary of the output transformer.

During operation, the control electrode of oscil-

lator tube 30 draws current causing a voltage drop in the biasing arrangement 32. Current at the predetermined carrier-signal frequency circulates in the oscillatory circuit 33, 34, developing between one end of inductor 33 and its tap a voltage at the carrier-signal frequency which passes through blocking condenser 35 and appears between the anode electrode of tube 30 and its grounded cathode. The voltage developed across the remainder of inductor 33 is applied regeneratively through the biasing arrangement 32 between the control electrode and the cathode of tube 30, causing the tube to oscillate when connected to a source of space current. Space current is provided from the source B+ through the secondary of transformer 25 and choke 31, so that the voltage causing space current to flow varies in accordance with the amplified modulating signal appearing in the secondary of the transformer. Variations in the anode voltage applied to tube 30 cause corresponding variations in the amplitude of the signal-frequency oscillations generated in unit 12. Accordingly, amplifier 11 and a part of tube 30 including its anode electrode constitute means coupled to source 10 and effective to vary the amplitude of the wave signals generated by unit 12 in accordance with the modulating signal to produce an amplitude modulated wave signal. The modulated signal-frequency energy is coupled from inductor 33 into the resonant circuit 36, 37 in the usual manner and thence applied to antenna 38 for radiation.

Variations occurring during modulation in the impedance coupled into the frequency-determining resonant circuit 33, 34 by transformer 25 and tube 30 tend to cause undesired deviation of the carrier frequency of the wave signals generated by unit 12. To compensate for the variations in impedance coupled into the oscillating circuit in this manner, an additional impedance comprising the impedance between anode 41 and cathode 42 of tube 40 is coupled across tube 30 and hence across the frequency-determining circuit 33, 34 through connection 15, condenser 35, and condenser 45. This additional impedance is adjusted to have the proper phase relationship to the voltage appearing across circuit 33, 34 by means of the phase-splitting network 47, 48 as modified by the inherent capacitance 49.

The proper adjustment of the impedance of tube 40 is obtained by virtue of the coupling of the phase-splitting network to resonant circuit 33, 34 through condensers 50 and 35 and through condenser 45 and the tap on inductor 33. This coupling causes signal-frequency current proportional to the carrier-frequency voltage across circuit 33, 34 to flow through the phase-splitting network. By making the resistance of resistor 47 large in proportion to the capacitive reactance of condenser 48, this carrier-frequency current is made to be essentially in phase with the voltage in the resonant circuit. Of course, condensers 50, 35, and 45 all should have sufficient capacitance so as to exhibit negligible impedances at the carrier frequency. The in-phase current through the phase-splitting network causes the voltage derived across condenser 48 to be substantially in phase quadrature with the voltage developed by the oscillatory circuit 33, 34, the derived quadrature component being applied to control electrode 43 of tube 40. Proper adjustment of the phase-splitting network makes the anode-cathode circuit of tube 40 effective as a reactance, thus placing a substantially reactive impedance in shunt with the oscillatory circuit.

The magnitude of the reactance exhibited by tube 40, however, is determined by the audio-frequency voltage which appears on the adjustable portion 54 of voltage divider 55 and thence passes through signal-frequency choke 52 to the control electrode 43. The modulating signal thus controls the transconductance from control electrode to anode of the pentode tube 40, so that by means of voltage divider 55 coupled to control electrode 43 the modulating signal is utilized to control the tube 40 and the entire frequency-modifying circuit 14. When the portion 54 of divider 55 and the reversing switch 23 are properly adjusted, the frequency-modifying circuit of unit 14 couples a compensating reactance into the frequency-determining circuit 33, 34 and this diminishes substantially the undesired deviation of the carrier frequency caused by amplitude modulation occurring in generator 12.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A frequency-stabilized wave-signal apparatus comprising, a generator of wave signals of predetermined carrier frequency, means effective to vary the amplitude of the wave signals generated by said generator in accordance with a modulating signal to produce an amplitude-modulated wave signal but tending to cause undesired deviation of the frequency of the wave signals generated by said generator, means coupled to said generator and effective to modify said carrier frequency, and means for utilizing said modulating signal to control said last-named means substantially to diminish said undesired deviation of said carrier frequency.
2. A frequency-stabilized wave-signal apparatus comprising, a generator of wave signals of predetermined carrier frequency, a source of modulating voltage, means coupled to said source and effective to vary the amplitude of the wave signals generated by said generator in accordance with said modulating voltage to produce an amplitude-modulated wave signal but tending to cause undesired deviation of the frequency of the wave signals generated by said generator, and means coupled to said generator and having a control arrangement connected to said source for utilizing said modulating voltage to modify said carrier frequency substantially to diminish said undesired deviation thereof.
3. A frequency-stabilized wave-signal apparatus comprising, a generator of wave signals of predetermined carrier frequency, a source of voltage varying in accordance with intelligence desired to be impressed upon said wave signals, means coupled to said source and effective to vary the amplitude of the wave signals generated by said generator in accordance with said voltage to produce an amplitude-modulated wave signal but tending to cause undesired deviation of the frequency of the wave signals generated by said generator, and means coupled to said generator and having a control arrangement connected to said source for utilizing said voltage to modify said carrier frequency substantially to diminish said undesired deviation thereof.
4. A frequency-stabilized wave-signal appara-

tus comprising, a generator of wave signals of predetermined carrier frequency including a first electron-discharge means, means effective to vary the amplitude of the wave signals generated by said generator in accordance with a modulating signal to produce an amplitude-modulated wave signal but tending to cause undesired deviation of the frequency of the wave signals generated by said generator, a second electron-discharge means coupled to said generator and effective as a reactance to modify said carrier frequency, and means for utilizing said modulating signal to control said second electron-discharge means substantially to diminish said undesired deviation of said carrier frequency.

5. A frequency-stabilized wave-signal apparatus comprising, a generator of wave signals of predetermined carrier frequency including a first electron-discharge means and an oscillatory circuit coupled thereto for developing a voltage at said carrier frequency, means including at least a part of said first electron-discharge means and effective to vary the amplitude of the wave signals generated by said generator in accordance with a modulating signal to produce an ampli-

5
